UNITED STATES PATENT OFFICE.

WILLIAM B. FENN, OF PORT WASHINGTON, NEW YORK, ASSIGNEE TO MARGARET F. FENN, OF PORT WASHINGTON, NEW YORK.

CORING AND TRIMMING MECHANISM.

Application filed December 29, 1923. Serial No. 683,815.

To all whom it may concern:

Be it known that I, WILLIAM B. FENN, a citizen of the United States, residing at Port Washington, in the county of Nassau, 5 State of New York, have made a certain new and useful Invention in Coring and Trimming Mechanism, of which the following is a specification.

This invention relates to coring and trimming mechanism such as is employed in machines for coring and/or trimming tomatoes, fruits, vegetables, or the like.

The object of the invention is to provide mechanism for the foregoing purposes, 10 which is simple in structure, efficient in operation and economical of manufacture.

A further object of the invention is to provide a combined coring and trimming device.

20 A further object of the invention is to provide mechanism of the character described which has certain structural features not incorporated in any device for similar purposes heretofore used.

25 Further objects of the invention will appear more fully hereinafter.

The invention consists substantially in the construction, combination, location and relative arrangement of parts and mode of 30 operation, all as will be more fully hereinafter set forth, as shown in the accompanying drawing and finally pointed out in the appended claims.

Referring to the drawing,

35 Fig. 1 is a view in side elevation of a combined corer and trimming device embodying my invention.

Fig. 2 is a central vertical section view of the same.

40 Fig. 3 is a top plan view of the same.

Fig. 4 is a vertical section view taken at right angles to the section shown in Fig. 2.

Fig. 5 is an enlarged detail view, partially in section, showing a corer blade.

45 Fig. 6 is a fragmentary top plan view of the coring blades in open position.

Fig. 7 is a view in side elevation of a trimming blade employed in accordance with my invention.

50 Fig. 8 is a top plan view of the same.

The same part is designated by the same reference numeral wherever it occurs throughout the several views.

55 In my co-pending application, Serial No. 550,643, filed April 8, 1922, patented Janu-

ary 1, 1924, as Number 1,479,061, I have shown and described a mechanically operated coring device for coring fruits, vegetables, or the like.

My present invention is directed to a 60 coring device of this nature, but contains various structural advantages thereover with respect to the coring mechanism.

My present invention also differs from the subject-matter of my above-identified 65 application in that it combines with the coring mechanism a trimming mechanism for trimming the fruit, vegetables, or the like, after the coring mechanism has been actuated.

70 As in the case of my co-pending application, above identified, while I have shown and will now describe my invention as being particularly adapted for use for extracting the cores from tomatoes and for 75 trimming the cored tomatoes, I do not desire to be limited or restricted in this respect, as the features of the invention therein contained may readily be utilized for extracting cores from other vegetables, 80 fruits, etc., and mechanical actuation of the device, while efficient, is not necessary.

Likewise, as in the case of my co-pending application above identified, I show a structure which is designed to be used in connection with a machine for removing the 85 skins of tomatoes, and wherein the structure consists of a base 1 having secured thereto guide plates 2, which guide plates are secured in any suitable manner, for example 90 by means of screws 3. The guide plates are placed on opposite sides of the base 1 and each of them is provided with one or more downwardly extending pins 4, which, in the form shown, are utilized for engagement with some advancing mechanism such, for example, as illustrated in my co-pending application above identified.

95 The base plate 1 is provided with a substantially circular orifice through the approximate center thereof, and secured to the plate 1 at substantially equi-distance apart, for example, by means of screws 5, are plates 6. In this instance three of such plates are employed. Each plate 6 secures to the body 100 1 a lower plate 7, each of which extends into the opening or orifice in the base 1, and the adjacent ends thereof form a pivotal support for the jaw members 8, 9 and 10, which will be more fully hereinafter 105 110

described. The jaw members are each pivotally mounted on adjacent portions of the respective plates 7. The other plate 6, which is held clamped to plate 7 by the screw 5, is provided with a flange portion 11 and the lip 12. The flange portion 11 and the lip 12 form a cutting annular recess between the lip 12 and the top of the base plate 1, it being understood that the plate 7 is counter-sunk relative to the base plate 1, at the edge of the orifice or opening through the center of the base plate 1. Held by the plate 6 with its flange and lip 11, 12 respectively, for rotary movement in the annular space above described, is what I will term the actuating ring 13. This ring contains a projection in the form of a pawl illustrated at 14, which, when engaged, serves to rotate the ring in one direction, in the form shown counter-clockwise, and substantially opposite thereto are provided two rounded projections 15 and 16 which, when rotated, serve to rotate the ring in the opposite direction, namely clockwise. The ring is also provided with three downwardly projecting lugs 17 spaced equi-distantly around the same, which lugs carry rigidly therewith pins 19. The jaws, as above noted, consist of the members 8, 9 and 10, the upper ends thereof being cut away and the respective members being pivoted at the approximate ends of their cut-away portions, so that when the jaws are rocked so that the upper ends thereof move towards each other, the contacting edges serve to cut the material encompassed therebetween from the rest of the body, whereas the opposite ends thereof are at a maximum distance apart. It is understood that the edges of these respective cutting members 8, 9 and 10 are sharp-edged to form in effect clippers.

Each of the jaws 8, 9 and 10 is provided with a cam groove 21. All of the jaws are similarly constructed with the cam groove 21 extending in an upwardly direction throughout the width of the jaw, but it will be readily apparent that when the three jaws are placed opposite each other in normal central position the cam grooves 21 extend in opposite directions with respect to any two thereof. The pins 19 which form part of the rotatable ring 13 extend through the cam grooves 21 respectively of the jaw members 8, 9 and 10, so that when the actuating ring is rotated in one direction, due to the cam action effect by the grooves 21 and the pins 19, the jaws are opened, and vice versa.

It will be seen from the foregoing that the coring device thus far described is substantially the same as that forming the subject-matter of my co-pending application, above identified, and differs therefrom largely in the provision of three jaw members in place of two thereof.

The operation in both cases is substantially the same; namely, the corer is normally maintained in the device with the jaws open which convert the cutters or jaws into substantially a cylinder, in plan view, as seen in Fig. 6. The tomato or other article to be cored is impinged upon the jaws 8, 9 and 10 so that the same encompass the core. It will be readily apparent that this will be facilitated when the edges of the jaws 8, 9 and 10 are knife-edged, as above described. The corer assembly, in the form selected for illustration, is then actuated by the chain which engages the pins 4, as described, until it is desired to cut out the core of the article, at which time the actuating ring 13 is rotated mechanically or otherwise by means of the lugs 15, 16, to the position shown in Fig. 4, whereby the core is cut out and allowed to drop through the open and extended bottoms of the jaw members 8, 9 and 10. When it is desired to again open the jaws, the lug 14 is mechanically or otherwise engaged to rotate the actuating ring in a counter-clockwise direction back to the position shown in Fig. 3.

It has been found in the practical operation of the corer, that while the corer operates efficiently and entirely satisfactorily, its efficiency can be increased by employing three coring blades instead of 2. It has also been found that in some instances, in handling a particular product of an exceedingly adhesive skin, the core tends to adhere somewhat to the skin, and in other products it is advisable or desirable to trim the product being operated upon to remove blemishes, skin adhesions, etc., in the same operation with the coring thereof.

I therefore have shown and will now describe a trimming device used in connection with the corer hereinbefore described.

The trimming device consists of a plurality of tooth-edged blades 30, preferably provided with their teeth on a bent portion of the blades bent normally with right angles with respect to the body thereof, as clearly illustrated in Fig. 2. These blades are positioned between the coring knives 8, 9 and 10 and the ring 13, and are pivotally supported at the edge of their approximate centers to the end of supporting arms 31 permanently secured to the body 1, as shown best in Figs. 2 and 8. Each of the trimming blades 30 is provided with a groove 32, which is likewise in the nature of a cam groove and through which the pins 19 of ring 13, which upon rotation of ring 13 actuate the corer blades 8, 9 and 10, likewise actuate the blades 30. As shown, I prefer to employ three trimming blades, one blade for each coring blade. It will be readily understood that by properly proportioning and controlling the direction of the cam groove 32 of the respective trimming blades, the

same may be made to operate at any desired time with respect to the operation of the corer. For example, the trimming blades may be made to operate about the 5 time of complete closure of the edges of the corer blades, so that trimming will be effected at the time the tomato or other vegetable or fruit is removed from the device.

Many modifications and changes in detail 10 will readily occur to those skilled in the art without departing from the spirit and scope of my invention as defined in the claims, and having shown and described a structure embodying the principles thereof, what I 15 claim as new and useful and of my own invention, and desire to secure by Letters Patent is:—

1. A trimming device for fruits, vegetables and the like, comprising a plurality of 20 fruit encompassing trimming blades adapted to be brought into contact with the outer surface of the article to be trimmed, and means for moving said blades.

2. A trimming device for fruits, vegetables and the like, comprising a plurality of curved blades adapted to be brought 25 into contact with the outer surface of the article to be trimmed, and means for moving said blades.

3. A trimming device for fruits, vegetables and the like, comprising a plurality of blades adapted to be brought into contact with the outer surface of the article 30 to be trimmed, means for mounting said blades at one end thereof for pivotal movement relative to each other, and means for simultaneously moving said blades to cause the opposite ends thereof to move towards 35 or away from each other.

4. A trimming device for fruits, vegetables and the like, comprising a supporting body having an orifice therein, trimming blades carried by said body at the approximate edge of the orifice, and means carried 40 by said body for actuating said blades.

5. A trimming device for fruits, vegetables and the like, comprising a supporting body having an orifice therein, trimming blades carried by said body at the approximate edge of the orifice, and a movable member carried by said body for simultaneously actuating said blades. 50

6. A trimming device for fruits, vegetables and the like, comprising a supporting body having an orifice therein, trimming blades carried by said body at the approximate edge of the orifice, and a rotatable member carried by said body for actuating said blades. 55

7. A trimming device for fruits, vegetables and the like, comprising a supporting body having an orifice therein, trimming blades carried by said body at the approximate edge of the orifice and provided with elongated slots therethrough, and a movable 60

member carried by said body and provided with pins extending through said slots, said slots being inclined relative to the plane of movement of said member.

8. A combined trimming and coring device, comprising a plurality of coring blades and trimming blades, and means for actuating said blades. 70

9. A combined trimming and coring device, comprising a plurality of coring blades 75 and trimming blades, and a common means for actuating said blades.

10. A combined trimming and coring device, comprising a plurality of coring blades mounted intermediate their ends for pivotal movement relative to each other, a plurality of trimming blades mounted at one end thereof for pivotal movement relative to each other, and means for actuating all of 80 said blades. 85

11. A combined trimming and coring device, comprising a plurality of coring blades mounted intermediate their ends for pivotal movement relative to each other, a plurality of trimming blades mounted at one end 90 thereof for pivotal movement relative to each other, and a common means for actuating said blades.

12. A combined trimming and coring device comprising a supporting body having 95 an orifice therein, coring blades located in said orifice and supported by said body, trimming blades also carried by said body at the approximate edge of said orifice, and means carried by said body for actuating 100 said blades.

13. A combined trimming and coring device comprising a supporting body having an orifice therein, coring blades located in said orifice and supported by said body, trimming blades also carried by said body at the approximate edge of said orifice, and a common means for actuating said blades. 105

14. A combined trimming and coring device comprising a supporting body having an orifice therein, coring blades located in said orifice and supported by said body, trimming blades also carried by said body at the approximate edge of said orifice, and a movable member carried by said body for simultaneously actuating said blades. 110 115

15. A combined trimming and coring device comprising a supporting body having an orifice therein, coring blades located in said orifice and supported by said body, trimming blades also carried by said body at the approximate edge of said orifice, and a rotatable member carried by said body for actuating said blades. 120

16. A combined trimming and coring device comprising a supporting body having an orifice therein, coring blades located in said orifice and supported by said body, trimming blades also carried by said body at the approximate edge of said orifice, all of 125 130

said blades being provided with elongated slots therethrough, and a movable member carried by said body and provided with pins adapted to extend through said slots, each pin extending through a coring blade and its adjacent trimming blade.

17. A combined trimming and coring device comprising a supporting body having an orifice therein, coring blades located in said orifice and supported by said body, trimming blades also carried by said body at the approximate edge of said orifice, all

of said blades being provided with elongated slots therethrough, a movable member carried by said body and provided with pins adapted to extend through said slots, each pin extending through a coring blade and its adjacent trimming blade, and means for moving said movable member.

In testimony whereof I have hereunto set my hand on this twenty-second day of December, A. D., 1923.

WILLIAM B. FENN.
